(57) **CLAIM**

The ornamental design for a grill guard, as shown and described.

DESCRIPTION

FIG. 1 is a top, front, and right side perspective view of a grill guard showing my new design in accordance to a first embodiment;

FIG. 2 is a top, rear, and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and

FIG. 8 is a bottom plan view thereof.

FIG. 9 is a top, front, and right side perspective view of a grill guard showing my new design in accordance to a second embodiment;

FIG. 10 is a top, rear, and right side perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken line showing a pair of brackets are for the purpose of illustrating portions of the grill guard and form no part of the claimed design.
